UNITED STATES PATENT OFFICE.

EDWARD M. EVARTS, OF NEW YORK, N. Y., ASSIGNOR, BY MESNE ASSIGNMENTS, TO
KUT-I-KORD KORPORATION, OF NEW YORK, N. Y., A CORPORATION OF NEW YORK.

CUTTER FOR CORD, TWINE, THREAD, AND THE LIKE.

Application filed November 19, 1923. Serial No. 675,481.

To all whom it may concern:

Be it known that I, EDWARD M. EVARTS, a citizen of the United States, and a resident of the borough of Manhattan, city, county, and State of New York, have invented an Improvement in Cutters for Cord, Twine, Thread, and the Like, of which the following is a specification.

My present invention relates to cutters for cord, twine, thread and the like, and aims to provide devices of the general character specified above, which will be very simple in construction, consisting of few parts; which may be readily, conveniently and cheaply fabricated; which will be easy to assemble and as easy to disassemble for repair or replacement of any of the parts thereof; which shall easily and conveniently permit the desired operation of cutting the cord, twine, thread or the like to be performed; and which shall possess other advantages in construction, mode of assembly, and operation subsequently set forth in greater detail herein.

In the accompanying specification I shall describe, and in the annexed drawing show, an illustrative embodiment of the present invention. It is, however, to be clearly understood that my invention is not limited to the specific embodiment thereof herein shown and described for purposes of illustration only.

Referring to the drawing, wherein I have shown the aforesaid illustrative embodiment of the present invention:

Fig. 1 is a side elevation of the device entirely assembled with the locking members for the cutting member and anvil secured in position; and

Fig. 2 is a similar view showing the cutting member and anvil in position within the supporting frame, but without the locking members for the same.

Referring to the aforesaid illustrative embodiment of the present invention, and more particularly to the drawing illustrating the same, 10 indicates generally the supporting frame comprising the main body portion of the device as a whole. This supporting frame comprises a base or standard 11 which may be provided with the apertures 12 for permitting the passage therethrough of screws or other fastening devices, not here deemed necessary to be shown, for attaching the device to any suitable support, such as

a store counter or the like. The frame 10 is provided with the two spaced and substantially parallel arms 20 and 21, one, such as the arm 20, for supporting the cutting member, generally indicated by reference character 30, and the other, such as the arm 21, for supporting the anvil, generally indicated by reference character 40. The two arms 20 and 21 are separated by a slot 22 which serves to admit the cord, twine, thread or the like for the cutting or severing operation.

The arm 20 which, in the example given, serves to support the cutting member, generally indicated by reference character 30, may be flat so as to accommodate the cutting member which is preferably a thin, two-edged cutting member, having the cutting edges 31 and 32, so that when one edge becomes dull the cutting member may be reversed and the sharp, unused edge placed in operative position in the frame 10. The arm 20 is preferably provided with a stud 33 for engagement with a central aperture 34 in the cutting member 30. Similarly, the cutting member 30 may be provided with a plurality of apertures 35 in alignment with the apertures 36 of the arm 20 and the apertures 37 of the locking member 38, which serves to position the cutting member 30 in place on the frame 20 by means of the screws or other fastening members 39. It will be noted that the locking member 38 is provided with the cut-away portion 38', so arranged as to expose the cutting edge 31 or 32, as the case may be, of the cutting member 30.

The anvil 40 is carried by the arm 21 in a depression 41 in the arm 21 and in a corresponding depression 50 in the inner face 95 of the locking member 51, which locking member serves to position and retain the anvil 40 in place in the device. The depressions 41 and 50 of the arm 21 and the locking member 51, respectively, serve also to position and retain in place a spring 42 which acts to press the anvil 40 towards the slot 22 against the cutting edge 31 or 32, as the case may be, of the cutting member 30. For this purpose a spring of the desired tension may be employed to facilitate the cutting or severing operation of the cord, twine, thread or the like, so as to make this operation comparatively easy, but so as to assure, at the same time, enough cutting pressure of the 110

cutting edge 31 or 32, as the case may be, of the cutting member 30 against the cord, twine, thread or other article being cut or severed. The arm 21 is provided with the 5 apertures 43 in alignment with the apertures 52 of the locking member 51 for admitting the passage therethrough of the screws or other fastening members 53 to hold the parts in proper position when the device 10 is assembled.

The anvil 40 may have any desired shape, but preferably has the shape shown in Figs. 1 and 2 of the drawing. As shown, the anvil 40 comprises a main body portion 44 against the rear edge 45 of which the spring 42 presses. The front edge 46 of the anvil 40 is curved at its upper portion, as indicated by reference character 47, and is provided with a slot 48 for receiving and 20 protecting the cutting edge 31 or 32, as the case may be, of the cutting member 30. Preferably, the slot 48 increases in depth from the upper portion to the lower edge 49 of the anvil 40. The inclination of the slot 25 48 should preferably be such that when the cutting member 30 and the anvil 40 are assembled in proper relation with respect to each other, the inner edge of the slot 48 will be substantially parallel to the cutting edge 31 or 32, as the case may be, of the cutting member 30. In this position of the cutting member 30 and the anvil 40, the designated members will be inclined with respect to each other, the operative 30 cutting edge of the member 30 being positioned within and protected by the groove 48 of the anvil 40, with such cutting edge substantially parallel, as already indicated, to the inner edge of the groove 48.

40 The manner of assembling the device described above will be substantially clear from the foregoing description. The manner of using the device will likewise be substantially clear from the foregoing description and may be briefly summarized as follows: The cord, twine, thread or the like desired to be cut or severed by the device of the present invention is passed with a quick, downward movement into the slot 22.

45 50 As a result of this downward movement it is brought into operative cutting or severing contact with the exposed portion of that edge of the cutting member 30 which is in operative position, in the present instance the cutting edge 32. It will be noted that the cord, twine, thread or the like being cut or severed will come into contact with the operative cutting edge of the member 30 at a point substantially below the upper- 55 60 most point of such cutting edge, and will be guided into operative cutting or severing contact with the upper rounded portion of the anvil 40.

The uppermost point of the operative cutting edge of the cutting member is protected and enclosed by the inclined position of the cutting member with respect to the arm 20 supporting the same, as more clearly shown in Figs. 1 and 2 of the drawing. By means of the spring 42 the desired degree of cutting or severing pressure is exerted upon the cord, twine, thread or the like being cut or severed. The spring 42 gives the anvil 40 the desired resiliency and thus facilitates the cutting or severing operation and results in a much cleaner job than would otherwise be accomplished.

The advantages of the device of the present invention in operation and use will be substantially clear from the foregoing description and may be briefly summarized as follows: By means of the construction described above, the cutting operation is conveniently and cleanly done with a minimum of effort. The operative cutting edge, as well as the inoperative cutting edge of the cutting member, is properly protected so as to minimize any chance that a person intending to use the device or actually using the same will be injured by the sharp cutting edges of the cutting member. The device itself is exceedingly simple in construction, easy to assemble and disassemble for repair or replacement of any of its parts, is neat and attractive in appearance, and possesses other advantages in construction, operation and use which will be apparent to those skilled in the art to which the present invention relates.

What I claim as my invention is:

1. In a cutter for cord, twine, thread and the like, a cutting member and an opposed, grooved anvil, the opposed edges of said cutting member and anvil being inclined with respect to each other, the groove of said anvil increasing in depth to correspond to the inclination of said anvil and cutting member as said opposed edges approach each other and accommodating the cutting edge of said cutting member.

2. In a cutter for cord, twine, thread and the like, a cutting member and an opposed, grooved anvil having a curved portion at its upper end, the opposed edges of said cutting member and anvil being inclined with respect to each other, the groove of said anvil increasing in depth as said opposed edges approach each other and the cutting edge of said cutting member extending within said groove and substantially parallel with the bottom wall thereof.

In testimony whereof, I have signed my name to this specification this 19th day of October, 1923.

EDWARD M. EVARTS.
